WEAVING HEDDLE

Paul Dathe, Hartha, Germany

Application July 3, 1936, Serial No. 88,883
In Germany July 5, 1935

1 Claim. (Cl. 139—95)

The present invention relates to weaving heddles and more particularly to heddles made from unsoldered double wire twisted together.

Weaving heddles made from unsoldered double wires twisted together are already known. It is further already known to make such heddles from only one unsoldered wire, bent into U-shape, and thus having double shanks, and to form the middle eye directly when twisting together the double wire. Going more into detail, the manufacture of these known heddles is effected by the double wire first being bent round in the end portions, and thereupon the middle portion of the double wire is twisted together and at the same time the middle eye and the end eyes formed. It is a drawback of this method that the making of the heddles is comparatively troublesome, can only be done mechanically with difficulty, and furthermore, in the end eyes the shanks of the double wire are not twisted together, but lie more or less parallel side by side, whereby the defect occurs that the two wire shanks of the end eyes easily become bent and thereby have a greater distance from each other and become unsuitable for weaving, especially with closely set warp threads.

The invention relates to a method of making weaving heddles of unsoldered double wire twisted together, which avoids these drawbacks, and according to the invention is characterized by the feature that the double wire, bent into U-shape or consisting of two parallel separate wires, is first twisted together and at the same time the middle eye formed, and only then bent round at the two ends to form the end eyes and the free ends of the wire connected to the heddle. By this method, first, the advantage is obtained that the heddles can be made in a particularly simple and certain manner mechanically and entirely automatically. Further, the advantage is obtained that the finished heddles made by the method have also considerable advantages over the known constructions. If, for instance, the method is so carried out that the double wire is twisted together over its whole length before the bending round of the end portions, also the end eyes are twisted together in the finished heddles, whereby a heddle of especially great strength is obtained, and any gaping apart of the wire shanks in the end eyes with the drawbacks associated therewith is avoided.

The term "double wire" employed herein is intended to mean either a single wire bent in U form with the arms of the U closely adjacent each other, or alternatively two separate wires laid together substantially in parallel.

The accompanying drawing shows the carrying out of the new method of manufacture by illustrating two stages of the work and also the finished heddle.

Figure 1 shows the first working operation by which the middle eye is finished and the double wire is twisted together over its whole length.

Figure 2 shows the second operation, in which the end portions of the heddle are bent round to form the end eyes.

Figure 3 shows a finished heddle made by the method according to Figs. 1 and 2.

The double wire 2, 3 bent into U-shape, or consisting of two parallel separate wires, is twisted together by rotating a middle eye pin 1 comparatively closely up to the points 4 and 5, at which, at first, stationary pins are inserted, so as to make the middle eye 6, and after removing the pins inserted at 4 and 5, twisted together somewhat more loosely over its whole length up to the clamps 7, 8. In a second working operation, the ends of the twisted wires are bent round end eye pins 9, 10 of suitable form to make the end eyes, the free ends of the wires held fast in clamps 11, 12, and by rotating the end eye pins 9, 10, the free ends of the wire are twisted together with the main part of the heddle or twisted into it. Any projecting ends of the wires are preferably cut off, so that the finished heddle has the form and construction shown in Fig. 3, or a similar one, in which also in the end eyes the double wire is twisted together.

If the double wire is not to be twisted together in the parts forming the end eyes, it is only necessary, without altering the method, to have the clamps 7 and 8 connected correspondingly nearer to the middle eye.

I declare that what I claim is:—

A weaving heddle formed of a plurality of wires and having a main portion and an end loop portion, said wires being twisted together throughout the main portion and the end loop portion, and the wire ends being twisted about the main portion to close the loop.
